(57) **CLAIM**

The ornamental design for a climbing structure play equipment as shown and described.

DESCRIPTION

FIG. 1.1: Perspective

FIG. 1.2: Front

FIG. 1.3: Back

FIG. 1.4: Left

FIG. 1.5: Right

FIG. 1.6: Top

FIG. 1.7: Bottom

FIG. 2.1: Perspective

FIG. 2.2: Front

FIG. 2.3: Back

FIG. 2.4: Left

FIG. 2.5: Right

FIG. 2.6: Top

FIG. 2.7: Bottom

The broken lines in the drawings show portions of the climbing structure play equipment which form no part of the claimed design.
